LIQUID-DISPENSING APPARATUS

Philip P. Krug, Harrison, N. J.

Application November 5, 1934, Serial No. 751,649

3 Claims. (Cl. 62—143)

This invention relates to dispensing apparatus and is designed more especially for dispensing beer in small quantities or by the drink. It is contemplated, according to my invention, that beer shall be delivered by the brewers in large glass jars or bottles and these bottles or jars shall be set upon an ice box through which the beer is drawn when it is to be served. It is a particular object of the invention to provide means whereby the jar or container will be sealed when delivered but access to the contents will be provided automatically when the jar is inverted and set in operative position upon the ice box. Other objects of the invention will appear as the description proceeds and the invention resides in certain novel features which will be particularly defined in the appended claims.

In the annexed drawing:

Figure 1 is a view, partly in elevation and partly in vertical section, of an apparatus embodying the invention.

Figure 2 is an enlarged detail section of the mouth of the jar and the adjacent portions of the ice box with the jar in position thereon.

Figure 3 is an enlarged detail section through the air delivery nozzle.

Figure 4 is a detail section through the mouth of the jar as the same appears before being set upon the ice box.

Figure 5 is a section showing a modification.

In the drawing, the reference numeral 1 indicates an ice box which may be of any desired formation and of any suitable material. In the top of the ice box is a hinged door 2 to facilitate placing of ice within the box, and at one end at the bottom thereof is a drain cock 3 to drain water from the box when the latter is to be cleaned. An overflow pipe 4 is also fitted in one wall of the box so that the cooling water in the box may be maintained at a desired level. Upon the top of the ice box is a rack or circular frame 5 which may be constructed of light rods or stout wire and is adapted to receive and support a large jar or bottle 6 which is preferably formed of glass in order that the contents of the jar may be noted at any time. In the wall of the jar is formed a conduit or air passage 7 which extends from the mouth of the jar to a point near the bottom of the same and at said point opens into the jar, as clearly shown in Figure 1. At the mouth of the jar a bung or cork 8 is tightly fitted and said bung or cork is formed with a central passage or opening 9 which is adapted to receive a nozzle 10 on the

end of an air pipe when the jar is fitted upon the ice box. When the jar is delivered by the brewer, a plug 11 is fitted closely in the opening 9 of the cork or bung 8 so that the end of the air passage is sealed and the beverage cannot escape from the jar through said passage. In a similar manner, the mouth of the jar has a bung or stopper 12 fitted tightly therein and said stopper or bung 12 has a central opening 13 in which is tightly fitted a plug 14 so that, when the jar is filled and delivered by the brewer, the contents of the jar will be effectually sealed against contamination. A coil 15 is disposed in the bottom of the ice box and has one end secured in a wall of the box at the bottom of the same and equipped with a faucet 16 through which the contents of the jar may be drawn as desired. The inner end of the coil 15 is carried upwardly within the tank, as shown at 17, and is connected by a collar or union 18 with a nozzle 19 which is adapted to enter the opening 13 in the stopper or bung 12 when the bottle is inverted and brought down over the end of the nozzle. As shown clearly in Figure 2, the nozzle is formed with an external flange 20 resting upon the top of the ice box and a gasket or washer 21 is disposed over said flange so that leakage of the beverage around the nozzle will be resisted. The nozzle is permanently secured within the ice box by solder or welding, as indicated at 22. The nozzle 10 is adapted to enter the opening 9 in the bung or cork 8 and is, like the nozzle 19, formed with a flange 23 which bears upon the top of the ice box and supports a gasket 24 upon which the end or mouth of the jar bears, as shown in Figure 2. The nozzle 10 is secured in the top of the tank by a coupling sleeve or collar 25 which is threaded onto the lower end of the nozzle, as clearly shown in Figure 3, and has its lower end threaded onto a nipple 26 which receives the end of a hose or flexible pipe 27, said pipe 27 extending through a side or end of the ice box to a source of air under pressure. Seated upon the nipple 26 is a check valve 28 in the form of a disc adapted to cover the bore of the nipple, as shown in Figure 3, and held to its seat by a retractile spring 29 which is anchored in the nipple at one end and has its opposite end attached to the valve, as shown and as will be understood. This check valve will permit the flow of air to and into the jar but will prevent reverse flow so that the proper aeration and pressure upon the beverage will be maintained.

From what has been said, it will be understood

that, when the jar is to be put into dispensing position, it is inverted so that the openings in the respective bungs or stoppers will be aligned with the respective nozzles 10 and 19 and then 5 the weight of the jar will cooperate with a slight pressure exerted thereon to force the same down over the nozzles, the nozzles bearing against the respective blocks 11 and 14 which will be thereby forced from the respective openings and will 10 float through the beverage and through the air passage 7 to positions immediately under the inverted bottom of the jar. The beverage will then flow by gravity from the jar to and through the coil 15 from which it may be drawn as de- 15 sired through the faucet 16. It will be noted that the coil and the lower portion of the pipe 17 are embedded in the ice and ice water so that the refrigerant will be applied directly to every portion of the surface of the coil except, 20 possibly, the small undersurface which may be in contact with the bottom of the tank, but it is also to be noted that when the parts are originally assembled the coil will be out of contact with the bottom of the tank so that its 25 entire surface will be subjected to the refrigerating action of the ice water.

In Figure 5 is shown a modification in which the nozzle 30 is coupled to the end of the dispensing pipe 31 just as the nozzle 19 is so coupled, but the nozzle 30 is formed with an auxiliary passage or bore 32 extending from a nipple 33 on the side of the nozzle and the air pipe 34 is coupled to said nipple. With this arrangement, the bung 8 and plug 11 are dispensed with 35 and the single nozzle will eject the plug 14 when the bottle or jar is forced down over the nozzle and the air will then enter directly into and rise through the beverage so as to aerate the same. In the first described form of the invention, 40 the air, of course, is admitted to the jar above the beverage and will exert pressure thereon, while in the form shown in Figure 5, the air rises through the beverage to reach the upper end of the jar and there accumulates to exert 45 the desired pressure upon the beverage.

In both forms of the invention the construction is simple and the jar may be easily set in place and when set in place will be automatically so disposed that communication between 50 the jar and the dispensing faucet is established. As shown in Figure 1, the jar is provided with a spiral or inclined lug or bead 35 which will facilitate the application of an outer cap covering both the bungs and thereby further protecting 55 the contents against contamination and also avoiding accidental release of the sealing plugs.

Having thus described the invention, what is claimed as new is:

1. A liquid-dispensing apparatus comprising a cooling chamber, a coil within the cooling chamber, a nozzle connected with the coil and rising 5 from said chamber, an air pipe passing into the cooling chamber, a nozzle connected with said pipe and rising through the top of the cooling chamber, a container having a side passage in its wall leading from the mouth of the container 10 to the bottom of the same and opening into the interior of the container at its bottom, a closure for the mouth of the container, a closure for said air passage, each of said closures having central openings, and plugs sealing said open- 15 ings and adapted to impinge upon the ends of the respective nozzles when the container is inverted over the nozzles whereby pressure upon the container will cause it to ride down over the nozzles and eject the plugs. 20

2. A liquid-dispensing apparatus comprising a cooling chamber, cooling means within the chamber, a nozzle connected with said cooling means and rising from said chamber, an air pipe passing into the cooling chamber, a nozzle 25 connected with said pipe and rising through the cooling chamber, a container having an air passage, a closure for the mouth of said container, a closure for said air passage, each of said closures being removable, and plugs sealing said 30 mouth and passage and adapted to impinge upon the ends of the respective nozzles when the container is inverted over the nozzles whereby pressure upon the container will cause it to ride down over the nozzles and eject the plugs 35 through said removable closures permitting removal of the plugs during a refilling operation.

3. A liquid-dispensing apparatus comprising a cooling chamber, cooling means within the chamber, a nozzle connected with said cooling 40 means and rising from said chamber, an air pipe passing into the cooling chamber, a nozzle connected with said pipe and rising through the cooling chamber, a container having an air passage, a closure for the mouth of said container, a closure for said air passage, a nipple, 45 a check valve carried therein and controlling air flow into the container, and plugs sealing the mouth of said container and said air passage and adapted to impinge upon the ends of the 50 respective nozzles when the container is inverted over the nozzles whereby pressure upon the container will cause it to ride down over the nozzles and eject the plugs. 55
